AUTOMATIC SHUTTLE REPLENISHING LOOM

Application filed September 15, 1930. Serial No. 481,841.

This invention relates to looms of the class in which provision is made for automatically removing an empty shuttle from a shuttle box and substituting a full shuttle when substantial exhaustion of filling is detected.

Automatic shuttle replenishing looms have been proposed heretofore and in some prior constructions the loom operation is suspended during shuttle replenishment, while in other proposed constructions the exhausted shuttle is replaced with a full shuttle during the loom operation.

In the constructions in which the loom is stopped to permit shuttle replenishment, the shuttle replenishing mechanism must be operated from an independent source of energy, and in looms of this type employing a belt drive it has been proposed heretofore to operate the shuttle replenishing mechanism from an independent, belt driven shaft that is operated from the source of power for the loom but independently of the loom and while the latter is at rest. In other constructions proposed heretofore electro-magnets have been employed to operate the shuttle transfer mechanism.

An extremely important feature of the present invention resides in an automatic shuttle replenishing loom having an electric motor that is separate and distinct from the loom driving mechanism and adapted to actuate the shuttle transfer mechanism.

Another important feature of the present invention resides in a shuttle replenishing loom having an electric motor to drive the loom and a separate motor to operate the shuttle replenishing mechanism, and provided with switch mechanism controlled by the condition of the filling to stop the loom and start the shuttle replenishing motor when substantial exhaustion of filling is detected.

A further feature of the invention resides in the cooperating electrical and mechanical means for stopping the loom motor and starting the shuttle replenishing motor when replenishment of filling is called, and for stopping the latter motor and starting the loom motor when the shuttle transfer is completed, and also in manually controlled

switch means for starting and stopping the loom motor.

Another feature of the invention resides in an electrically controlled brake associated with the loom motor to quickly stop the loom, and in electrical switches under the control of different operating parts of the loom and operable to cut off the current to the loom motor and apply the brake to quickly stop the loom when a defect in the weaving operation occurs.

Still other features of the invention reside in the mechanism for ejecting an empty shuttle from a shuttle box and for transferring a full shuttle from the shuttle magazine to the shuttle box, and in the filling feeling mechanism for initiating shuttle replenishment.

Other features of the invention and novel combination of parts in addition to the above will be hereinafter described in connection with the accompanying drawings, which illustrate a carpet loom embodying the construction of the present invention.

In the drawings:—

Fig. 1 is a perspective view of a pile fabric loom provided with the shuttle replenishment mechanism of the present invention;

Fig. 2 is a side elevation with parts in section of the loom of Fig. 1;

Fig. 3 is an enlarged transverse sectional view through a shuttle box and shows the filling feeling mechanism.

Fig. 4 is a front elevation of the filling feeling mechanism of Fig. 3, the lay being omitted.

Fig. 5 is a vertical sectional view through the shuttle supply magazine and lay, the shuttle box being shown open in full lines and closed in dotted lines.

Fig. 5^a is a perspective view of a detailed part of Fig. 5 to be described;

Fig. 6 is a vertical sectional view showing the shuttle box of Fig. 5 slightly open;

Fig. 7 on a reduced scale is a top plan view of the shuttle supply magazine and adjacent shuttle box;

Fig. 8 is a longitudinal sectional view

through a gear box containing the operating cams for the transfer mechanism;

Fig. 9 is a front elevation of a portion of the loom with the gear box of Fig. 8 shown in section.

Fig. 10 is a top plan view of a shuttle in the right shuttle box, and of the cooperating filling feeler.

Fig. 11 is a top plan view of the pile wire actuating mechanism;

Fig. 12 is a vertical sectional view through the wire guiding slot showing a pile wire in sliding engagement therewith;

Fig. 13 is a top plan view of beam let-off mechanism of the loom;

Fig. 14 is a perspective view of a filling fork and filling shearer in place upon the loom;

Fig. 15 is a diagrammatic view of the electrical connections for controlling the loom motor and shuttle replenishing motor; and

Fig. 16 is a front view with parts in section of a master switch to be described.

The automatic shuttle replenishing mechanism of the present invention may be employed upon various types of looms but is illustrated in the drawings as applied to a pile fabric loom of the pile wire type.

The loom illustrated in the drawings has been designed more particularly for use in weaving carpet, and contains a number of new and highly desirable features in addition to the shuttle replenishing mechanism claimed herein. Practically the entire loom has been herein shown and described to make clear the location, function and general mode of operation of the loom in its entirety.

The present application therefore constitutes the parent case and the novel features shown and described but not claimed herein are to be made the subject of separate applications.

The loom shown has the side frames 1 and 2 of the usual or any suitable construction for supporting the operating mechanism and these side frames are secured in spaced relation to each other by the braces 3 and other connections shown. The side frames 1 and 2 are provided with the elevated columns or structure 4 and 5 adapted to support the harness mechanism and a warp beam, and the columns 4 and 5 are connected by the rails 6.

At the front of the loom is provided the usual spike or take-up roll 7, the ends of which are journaled in the bearings 8 secured to the frames 1 and 2 and this roll is operated from mechanism to be described to take up the fabric F as woven.

At the rear of the roll 7 is provided the lay 9 which is supported by the lay swords 10 and shaft 11 for rocking movement towards and from the front of the loom in a well known manner, and the lay is provided at its opposite ends with the pickers 12, op-

erated by the picker sticks 13. The beat-up movement is imparted to the lay 9 by the crank shaft 14 and pitman rods 15, as usual, and mounted upon the lay is the reed 16, the upper portion of which is supported by the reed cap 17 secured to the upper ends of the lay swords by the brackets 18.

Since the loom illustrated is designed for weaving pile fabric, the loom is shown as provided with the upper warp beam 19 rotatably supported by the columns 4 and 5 and this beam carries the yarn warp a. In the construction shown the stuffer yarn b is supplied from the stuffer beam 20 rotatably mounted between the side frames 1 and 2 at the rear of the loom, and the supporting shaft of the beam 20 is journaled in the bearing brackets 21. The chain warp c is supplied from the chain beam 22, which is shown as supported in front of the stuffer beam 20 by the bearing brackets 23.

The arrangement of the three let-off beams just described, is such that an unusually large yarn warp beam 19 and stuffer beam 20 may be employed, as will be apparent from Fig. 2 of the drawings. In some cases it may be desirable to remove the chain beam 22 without cutting the stuffer yarns b, and to facilitate this the stuffer beam 20 is provided, in accordance with the present invention, with the beam elevating levers 24 disposed at the opposite sides of the loom and rigidly secured to the shaft 25 which extends between them and is rotatably supported by the side frames 1 and 2. The arrangement is such that when it is desired to elevate the stuffer beam 20 to permit the removal of the chain beam 22, this is readily accomplished by removing the cap plates of the bearings 21 and 23. The stuffer beam may then be elevated by connecting a chain hoist or other elevating means with the hook portion 26 of each lever to pull the levers 24 upwardly about the pivoted shaft 25 to elevate the beam 20.

The levers 24 may be retained in their elevated position by providing each lever with an arcuate bracket 27 having the noteh 28 adapted to be engaged by the sliding pin 29 when the levers 24 are swung upwardly to substantially a horizontal position. The levers 24 may be released to move downwardly to the position in which they are shown in full lines in Fig. 2 by retracting the sliding pins 29.

The stuffer yarns b pass from the beam 20 under the shaft 30 and over the whip roll 32 that is supported for yielding rocking movement, in a well known manner, by the arms 31, and the chain warps c are led upwardly over a second and similarly supported whip roll 32. In front of the forward whip roll 32 is preferably provided the warp stop mechanism 33 which may be of any well known construction and arranged to be operated to stop the loom when a warp thread

b or *c* breaks or becomes too slack. This warp stop mechanism preferably has associated therewith an electric switch, to be described, for stopping the loom when a defect in the 5 warp occurs. A similar warp stop mechanism 34 is preferably provided for the yarn warps *a*, which are shown as passing over the shaft 35 and then downwardly about the whip roll 36 supported by the rocking arms 10 37 and from this point the warps pass forward through the heddle frame and reed 16 to the fell of the cloth.

The harness mechanism of the loom illustrated employs four heddle frames 38, one 15 for the yarn warps, one for the stuffer warps, and two for the chain warps. These heddle frames are operated by a novel form of mechanism for positively raising and lowering the frames as desired. Each heddle 20 frame 38 preferably is constructed of light skeleton steel and is supported by the looped end portions of a flexible cable or other flexible means, the intermediate portion of which is bent about a grooved sheave carried by a 25 pulley 39, and the pair of flexible strands 40 and 41 formed by looping the wire or the like about the pulley sheave 39 extend upwardly over a grooved roller 42, and one of these strands 40 passes downwardly about a 30 grooved roller 43 to support the heddle frame 38 near one end thereof while the other strand 41 extends downwardly about a roller 44 to support the heddle frame near the opposite end thereof, as will be apparent from 35 Fig. 1 of the drawings.

The ends of the strands 40 and 41 are looped about cable receiving portions carried by the upper part of the heddle frame and then fastened to the downwardly extending strand by a clamp 45, as shown. Each 40 of the four heddle frames 38 shown is supported from the upper structure 6 of the loom in the manner just described by the looped strands 40, 41 of one of the four flexible cables shown.

The lower side of each heddle frame 38 is similarly connected to the spaced looped strands 46 and 47 of an operating cable, or other flexible connection. These strands 46 50 and 47 for a heddle pass downwardly about the lower rollers 48 and then upwardly about the sheave 48^a to a pulley 49 positioned below the heddle operating lever 50 for that cable.

55 The movement of each heddle frame 38 is at all times positively controlled by one of the four heddle levers 50. These levers are pivotally supported at 51 and each receives its operating movement from a grooved cam 60 52, adapted to engage a ball or roller, not shown, but secured to an intermediate portion of its lever 50, to operate in a well known manner to positively control the movement of the heddle lever. The heddle operating cams 52 are mounted upon and operated by

a projecting portion of the bottom shaft 53.

Each upper pulley 39 is connected to its heddle lever by a turn buckle 54 and link or the like 55, and the corresponding lower pulley 49 is similarly connected to its heddle lever by a turn buckle and link connection. The arrangement is such that should a heddle frame be tilted out of the desired horizontal position it can readily be restored to the horizontal position by loosening the clamps 56 75 provided upon the heddle operating cables adjacent the pulleys 39 and 49, whereupon the strands 40, 41 and 46, 47 connected to a heddle frame may be shifted about their co-operating rollers, and the sheaves of the pulleys 39 and 49 to bring the heddle frame into the desired horizontal position. The clamps 56 may then be tightened to maintain the frame in a horizontal position. The flexible operating connections for the heddle frame 80 are preferably formed of relatively small but strong and highly flexible cables which will travel freely about their rollers even when maintained under strong tension. The vertical adjustment of the heddle frames relative to the lay and the desired tension upon the cables is readily secured by providing the upper and lower cables with the turn buckles 54. The harness mechanism of the present invention controls the movement of the heddle frames with a high degree of accuracy 85 and is to be made the subject of a separate application.

Another novel feature of the present loom resides in the construction and operation of the picking mechanism for operating the picker sticks 13. In the embodiment of the invention illustrated each picker stick 13 is operated from the crank shaft 14 by a downwardly inclined picking shaft 57 which 100 is supported near its opposite ends by the brackets 58 for sliding movement in the direction of its length. The picking shaft is provided near its lower end with an arcuate picking shoe 59, which is rigidly secured to the shaft 57 to be actuated thereby, and the outer end of this shoe is connected to the picker stick by the strap 60. The picking shaft 57 is provided near its upper end with an operating tongue 61 adapted to be engaged and rocked by a cam ball or roller 62 105 adjustably mounted on the picker disc 63.

The construction is such that the crank shaft 14 is provided at each side of the loom with a picker disc 63 adapted to be rotated 110 by the crank shaft, and the cam ball or roller 62 secured upon one picker disc is disposed at an angle of 180 degrees to the cam ball or roller upon the other disc. The picking shaft 57 at each side of the loom normally remains in its lowered position in which it is shown in full lines in Fig. 2, and as long as the shaft is 115 in this position the operating tongue 61 lies below the path of the cam ball 62 so as not to be operated thereby. When the picker

stick at one side of the loom is to be operated the picking shaft for operating that stick is momentarily raised so as to bring its tongue in position to be engaged and operated by the cam ball 62 to impart the desired movement to the picker stick.

The means shown for temporarily raising a picking shaft 57 consists of a lever 64 pivotally supported intermediate its ends at 65 and one end of this lever is preferably constructed so as to straddle the rocking shaft 57 and is provided with the pins 66 adapted to enter the annular groove between spaced discs on the shaft 57, so that the shaft 15 may be elevated by rocking the lever 64 from its full line position of Fig. 2 to its dotted line position of this figure. The desired rocking movement is imparted to the lever 64 at one side of the loom by a cam 67 secured 20 to the bottom shaft 53 as shown in full lines in Fig. 2 and the lever 64 at the opposite side of the loom is similarly operated by the cam 67 as shown in dotted lines in this figure. In the particular construction shown the bottom 25 shaft 53 is driven from the cam shaft 14 by the pinion 68 and gear 69 at a ratio of one to four, and each of the cams 67 is provided with two lever actuating portions disposed 180 degrees apart, the arrangement being 30 such that during one complete rotation of the bottom shaft 53 the picker stick at each side of the loom will have two picking movements imparted thereto.

It is necessary that the fabric W be advanced towards the front of the loom at the proper speed, since the number of picks laid per inch depends to a large degree upon the rate at which the take-up mechanism for the fabric is operated. In the construction shown 40 the fabric F is moved forward by positively driving the spike or take-up roll 7 from a going part of the loom, and the fabric passes around the take-up roll 7 and then downwardly to the cloth roll 70, shown in Fig. 2, 45 but not in Fig. 1, the ends of the roll 70 being rotatably supported by the bearing brackets 71. In the embodiment of the invention illustrated the spike or take-up roll 7 is positively driven from the bottom shaft 53 50 through a worm upon the bottom shaft which meshes with a worm wheel 72. This worm wheel operates the driving shaft 73 provided adjacent its opposite ends with the universal joints 74 and provided at one end with the telescopic connection 75. The shaft 73 serves 55 to drive the change gear 76 mounted upon a shaft which is journaled in the bearing bracket 77 and this bracket is adjustably secured to the side frame of the loom by the bolts 77. The arrangement is such that the change 60 gear 76 drives the upper gear 78 and the speed at which the upper gear is operated from the bottom shaft 53 may be varied as desired by employing different size change gear 76. This is facilitated by the vertical

adjustment of the bearing brackets 77, that support the change gear.

The upper gear 78 serves to drive the shaft 79 having rotatably mounted thereupon the worm 80 adapted to drive the worm wheel 81 secured to the shaft of the spike or take-up roll 7.

Since it is desirable from time to time to release the take-up roll from its positive driving connection to permit the manual rotation of the roll, means are provided whereby the take-up roll may be readily actuated either manually or automatically, and to this end in accordance with the present invention a ring gear having external and internal teeth is bolted or otherwise secured to the outer end of the worm 80. Keyed to the shaft 79 for sliding movement thereupon is a gear 82 adapted to be moved into and out of interlocking engagement with the internal 80 teeth of the ring gear. The arrangement is such that the gear 82 may be moved inwardly to cause the worm 80 to be positively driven from the shaft 79, and may be moved outwardly to permit the take-up roll to be operated independently of this shaft, the gear being shifted by engaging the nob 83 between the fingers. When the interlocking sliding gear 82 is shifted out of engagement with the ring gear, the latter may be manually rotated from the stub shaft 84. The projecting end of this shaft is adapted to receive an operating crank handle, and the shaft is provided with a pinion 85 which meshes with and rotates the ring gear. The various gears just described are preferably enclosed in a casing 86, shown in Fig. 2.

The novel features of the take-up mechanism just described are to be made the subject of a separate application.

Various means might be provided for rotating the cloth roll 70 to wind the cloth thereupon as it is pulled forward by the spike or take-up roll, and in the construction shown the take-up roll 70 is yieldingly driven in the cloth take-up direction by the rocking lever 87, which is supported by the fixed pivot 88, see Fig. 2. The rearwardly extending portion of the lever 87 is normally urged downwardly by the coiled spring 89 and this lever is provided at its rear end with the forked prongs 90. The upper prong is curved as shown and is adapted to be engaged and elevated as the lay beats up by the projection 91 extending laterally from the lay sword 10. The arrangement is such that the rocking movement of the lever 87 will actuate the pawl 92 carried by this lever to engage and rotate the ratchet wheel 93 of the cloth roll in the direction indicated by the arrow. If the tension upon the cloth is sufficient to maintain the lever 87 in its raised position then the latter will not be actuated by the movement of the lay until the tension upon the cloth is decreased.

The take-up mechanism above described serves to positively advance the fabric W forward at a predetermined speed with respect to the loom operations. It is therefore desirable to provide means controlled by the tension of the warp threads *a*, *b* and *c* to regulate the unwinding rotation of the beams 19, 20 and 22 to thereby maintain a constant tension upon the various warp threads. Having this in mind the novel construction of the let-off mechanism illustrated in the drawings will now be described.

The let-off mechanism shown for the stuffer beam 20 and chain beam 22 is similar in construction and each of these beams is provided with the worm wheel 94 and worm 95 cooperating therewith and each worm 95 is secured to a vertical shaft 96, having associated therewith a let-off brake 97.

Unwinding rotative movement is imparted to each of the beams 20, 22 by slowly rotating the shafts 96 from a going part of the loom, and the operation of this unwinding movement is controlled by the tension of the warp threads *b* and *c*. This is accomplished in the construction shown by providing each of the shafts 96 with a ratchet wheel 98 (see Fig. 13) adapted to be rotated by a pawl 99 carried by the lever 100, which is mounted upon the shaft 96 for rocking movement. The rocking movement is imparted to each of the levers 100 in the construction shown, from the cam shaft 14 through the employment of the eccentric 101, mounted upon this shaft and operatively connected to the levers 100 by the links 102 and 103. The arrangement is such that each complete rotation of the cam shaft 14 imparts rocking movement to the levers 100 to actuate the pawls 99. The amount of rotative movement imparted to the shafts 96 by the pawls 99 during one stroke of the lever 100 is controlled in the present case by a pawl guard 104, which is pivotally mounted upon the shaft 96 between the pawl 99 and ratchet wheel 98. The construction is such that this guard plate is positioned in accordance with the tension of the warp threads to control the operating stroke of the pawl 99. This is accomplished by providing the whip roll mechanism above described with a downwardly extending arm 105 to which the pawl guard 104 is connected by a link 106. It will be understood that the whip roll 32 is normally urged in the warp tensioning direction by weight or spring means in a well known manner, and the movement of this whip roll in a left-hand direction, viewing Fig. 2, will serve to cut down the effective stroke of the pawl 99, while the movement of this roll in the opposite direction will serve to increase the active stroke of the pawl 99.

The let-off mechanism illustrated in the drawings for controlling the unwinding ac-

tion of the yarn warp beam 19 is different from that just described as the beam 19 is provided at one end with a brake drum 107, about which extends the brake band 108, which is anchored at one end at 109. The opposite end of this brake band is secured by the connecting means 110 to the intermediate portion of the lever 111 which is pivotally secured to the loom frame at 112. The outer end of the lever 111 is continuously urged downwardly by the spring 113 in a direction to increase the friction of the brake band 108 upon the brake drum. The whip roll 36 above described is continuously urged in the warp tightening position by the compressed coil spring 114, which surrounds the rod 115, the lower end of which rod is pivotally fastened to the lever 116, that is secured to and extends laterally from the shaft 35. The shaft 35 is provided with a finger 117 to raise the lever 111 as the whip roll 36 is moved forwardly by the tension the warp *a* in opposition to the downward pressure exerted upon the lever 116 by the spring 114.

Many of the features so far described in the present application, constituting the parent case, are believed to be new and patentable, but are not claimed herein since the present application is directed more particularly to the general construction of the carpet loom and the shuttle transfer features, which will now be described.

As above pointed out an outstanding feature of the present invention resides in the electrically controlled and actuated means for effecting automatic shuttle replenishment. It will be understood that these electrical features may be employed in connection with various forms of mechanical means for effecting the shuttle transfer.

The lay is provided at its left-hand end in Fig. 1 with a shuttle box, the rear wall 118 of which, see Fig. 5, has a binder or swell 119 of usual construction, and the front wall or plate 120 of the shuttle box is supported by a pair of spaced arms 121 for movement to and from the shuttle engaging position. The arms 121 are adjustably secured to brackets 122 secured to the rocking shaft 123.

This shaft is rotatably supported by the spaced brackets 124 that are rigidly secured to the rear portion of the lay. The arrangement is such that the front wall or plate 120 is normally held by the strong spring 125 in the lowered position in which it is shown in dotted lines in Fig. 5, but may be rocked upwardly to the position in which it is shown in full lines in Fig. 5 by operating means to be described.

This rocking movement is imparted to the shaft 122 and front plate 120 of the shuttle box by a rearwardly extending arm 126 which is actuated by a downwardly extending rod 127. Projecting downwardly from the rocking shaft 122 are the ejector actuating arms

128, each of which has pivotally secured to its lower end an ejector 129, the free end of which extends into a hole 130 formed in the rear wall of the shuttle box. The arrangement is such that when the rod 127 is pulled downwardly to elevate the plate 120, the ejectors 129 are forced into the shuttle box to eject an empty shuttle 131, as will be apparent from Figs. 2 and 5, whereupon the shuttle will slide down the guiding apron 132 into the box 133.

The full shuttles 134 are supplied to the shuttle transfer mechanism by the shuttle magazine 135, which is positioned at the left-hand side of the loom frontwardly of the lay. The magazine is adjustably secured to a bracket 136 mounted upon the loom frame. This bracket adjustably supports the laterally extending shaft 137, to which the magazine is clamped. The shuttles in the magazine 135 are normally prevented from dropping out of the lower end thereof by the holder 138, which is supported by the rocking arms 139 and shaft 140, the arrangement being such that a spring 141 continuously acts upon the arms 139 in a direction to urge the holder 138 to a position beneath the stack of shuttles.

The shuttle transfer mechanism comprises the shuttle support 142 carried by the shuttle inserting lever 143, and this support is normally held by its lever below the shuttle magazine and slightly in front of the position in which it is shown in Fig. 5. When shuttle replenishment is called, the lever 143 is momentarily moved frontwardly, by operating mechanism to be described, into the position in which it is shown in Fig. 5, so that the finger 144 upon the lever 143 will engage a downwardly extending portion 145 of the holder 138 and move the holder to the position in which it is shown in Fig. 5, to permit the lowermost shuttle to drop into the shuttle support 142. The lever 143 is then moved rearwardly towards the lay, which is now in its back position with the front plate 120 elevated as shown in full lines in Fig. 5. As the shuttle support 142 moves rearwardly from the position in which it is shown in Fig. 5, the holder 138 will be moved by the spring 141 beneath the magazine 135 to support the shuttles therein.

The empty shuttle 131 is discharged from the shuttle box by the ejectors 129 in time to make room for the full shuttle 134, and the shuttle holder 142 is so supported by the lever 143 that it may move into the shuttle box as will be apparent from Fig. 6, and while the parts are in this position the wall 120 of the shuttle box is lowered to the position in which it is shown in Fig. 6 to maintain the shuttle in the shuttle box while the shuttle inserting lever 143 is moved away from the lay. As soon as the shuttle support 142 has been moved clear of the lay the front wall may be lowered

to its normal loom operating position in which it is held during weaving by the spring 125, the wall 120 being supported in its lowermost position by the adjustable bolts 146. In the construction shown safety latches 147 are pivotally supported from the hopper so as to lie below the shuttle carrier 142, as shown in Fig. 5, the arrangement being such that should the rearward movement of the holder 138 fail to separate a pair of shuttles, the lowermost shuttle will drop upon the safety latches 147 to be supported thereby until these latches are rocked frontwardly by the return of the shuttle inserting lever to its position below the magazine.

It will be seen from the foregoing description of the shuttle transfer mechanism that the transfer of a shuttle from the shuttle magazine to the shuttle box is effected through the operation of the shuttle inserting lever 143, and front plate positioning rod 127. The electrical means for securing the proper operation of this rod and lever will now be described.

As previously stated an important feature of the present invention resides in electrical means for actuating the shuttle transfer mechanism and this means in the construction shown comprises an electric motor 148, which may be relatively small as compared to the size of the loom operating motor, to be described. The motor 148 may be mounted upon a base plate 149, secured to the gear box 150. Within this gear box in the construction shown is rotatably supported the worm shaft 151 provided with a worm 152, and this shaft is operatively connected to the driving shaft of the motor 148 by the coupling 153. The worm 152 drives the worm wheel 154 and its supporting shaft 155.

The shaft 155 is provided with a pinion 156 driven by the shaft to rotate the gear 157 keyed or otherwise secured to its supporting shaft 158. Rigidly secured to the shaft 158 is the ejector cam 159 adapted to engage the roller 160 secured to the intermediate portion of a lever 161. One end of this lever is mounted upon the fixed pivot 162 while the opposite end of the lever is pivotally connected at 163 to the downwardly extending rod 127. This rod, as above pointed out, serves to control the position of the front plate 120 and the effective length of the rod 127 may be adjusted by rotating the nut or turn buckle 164. The construction of the cam 159 is such that when the loom is operating and the motor 148 is at rest this cam will occupy the position in which it is shown in Fig. 8, where it will be seen that the roller engages that portion of the cam which is sufficiently small in diameter to permit the front plate 120 of the shuttle to be held by the spring 125 in its lowermost position.

As soon as the motor 148 is started to ef- 130

fect shuttle transfer the cam 159 will be rotated by the gear connections in the direction indicated by the arrow in Fig. 8. This will cause the nose portion 165 of the cam 159 to 5 depress the lever 161 sufficiently to move the shuttle wall 120 upwardly to its maximum position of Fig. 5, so that the ejectors will discharge the empty shuttle 131 from the shuttle box, whereupon the arcuate portion

10 of the cam of less diameter than said nose will engage the roller 160 to support the shuttle wall 120 substantially in the position in which it is shown in dot-and-dash line of Fig. 5. When the cam 159 has rotated 15 through a substantial portion of a complete revolution the roller 160 will engage the portion thereof of smallest diameter to permit the front wall 120 to be again moved to its closed position.

20 The cam shaft 158 is provided with a second cam 166 for operating the shuttle inserting lever 143. The lower end of the lever 143 is pivotally supported by a bracket 167 upon the loom frame and the lever 143 is continuously urged in a rearward direction by the spring 168. The actuation of this lever to effect shuttle transfer is secured in the construction shown by the bell crank lever 169, which is supported by the fixed pivot 170, 25 and the upwardly extending arm of this bell crank lever is connected to the lever 143 by the adjustably connecting link 171, while the laterally extending arm of this lever is provided with a roller 172 adapted to engage the cam 166. This cam, it should be noted, is provided with the projecting nose 173 adapted to momentarily move the shuttle inserting lever 143 forwardly an abnormal amount to actuate the holder 138 to thereby release a shuttle 30 from the magazine. As soon as this is accomplished the further rotation of the cam 166 will permit the lever 143 to move rearwardly under the action of the spring 168 and transfer the full shuttle to the shuttle box 35 and then return this lever to its normal position below the shuttle magazine.

The operation of the lever 143 and rod 127 by the cams 159 and 166 to effect shuttle replenishment takes place during one complete 40 rotation of this shaft, the arrangement being such that the motor 148 is stopped by mechanism, to be described, each time the shaft 158 is rotated thereby through a complete rotation.

45 Having described the shuttle transfer mechanism and the motor operated means for actuating the same, the filling control means for initiating shuttle transfer will now be described. This is accomplished in the embodiment of the invention illustrated by employing a filling feeler 174 which is located at the right hand side of the loom in Fig. 1, and the feeler is illustrated in Fig. 10 of the drawings as adapted to feel the condition of 50 a shuttle 134 having a hinged part or gate

175 mounted in an opening in a side wall of the shuttle so that the gate will be held in its outermost position as long as there is a substantial amount of filling in the shuttle, but will be pressed inwardly by the feeler 174 during the filling feeling operation when the filling in the shuttle is approximately exhausted.

55 It will be apparent, however, that other forms of feeler mechanism may be employed in carrying out the features of the present invention. The filling feeler 174 is pivotally secured at its forward end to an arm 176 that extends upwardly from the detector shaft 177 that is pivotally supported by brackets secured to the loom frame, and the feeler is held in substantially a horizontal position opposite the opening in the shuttle box by a downwardly extending pin 178. The detector shaft 177 is provided adjacent its opposite end with a downwardly extending arm 179, see Fig. 5, and to this arm is connected a rearwardly extending rod 180 adapted to control the position of a rocking latch 181, pivotally secured at 182 to the outer end of a switch operating lever 183. The lever 183 is pivotally supported at 184 and is continuously urged forwardly towards the stop 185 by the spring 186. The latch 181 is provided with the stop 187 adapted to strike the lever 183 when the latch is rocked upwardly to the position in which it is shown in Fig. 5 and the latch is continuously urged to this position by its spring 188. The construction of the latch 181 is best shown in Fig. 5^a where its downwardly extending arm 189 is shown as provided with a slot 190 adapted to slidably receive the rear end portion of the rod 180.

60 The operation of the filling feeling mechanism just described is such that the rod 180 is relied upon to hold the latch 181 in its inclined or inactive position of Fig. 3, and to this end the rod 180 is provided with a collar 191 secured in position to abut against the arm 189 of the latch to hold the same tilted.

65 When on a detecting beat there is sufficient filling in the shuttle to prevent the gate 175 from yielding inwardly under the pressure of the feeler 174, this feeler will be pushed forwardly by the gate 175 and this will thrust the rod 180 rearwardly sufficiently to tilt the latch 181 out of the path of the abutment or bolt 192 carried by the lay. If, however, the feeler 174 detects substantial exhaustion of filling in the shuttle, then the feeler will not be pushed forwardly by the gate 175 far enough to cause the latch 181 to clear the bolt 192, and as a result the latch 181 and lever 183 will be forced rearwardly 70 as the lay goes back as shown in Fig. 5. Movement of the lever 183 rearwardly causes a dog 193 carried thereby to rotate the ratchet wheel 194 and toothed cam wheel 195 to 75 depress the switch actuating roller 196, see 80

Fig. 3. This will operate a switch within the switch box 197 to stop the loom and start the replenishing motor 148 in a manner to be described. The electrical conductors leading to the switch box 197 may be enclosed in the armored cable 198.

It will be understood from the construction just described that when a shuttle containing a substantial amount of filling is in the right-hand shuttle box as the lay beats up, the filling controlled gate 175 of the shuttle will not yield inwardly under the pressure of the feeler 174, and as a result the rod 180 will be shifted rearwardly far enough to hold the pivoted lever 181 out of the path of the bolt 192. If, however, the filling in the shuttle is sufficiently exhausted to permit the gate to move inwardly under the action of the feeler, then the forward movement imparted to the feeler by the lay will not be sufficient to rock the pivoted lever 181 out of the path of the bolt 192 with the result that the lever 183 will be actuated by the lay movement to operate the switch mechanism and stop the loom driving motor and start the shuttle replenishing motor 148.

It is important that means be provided for holding the pivoted lever 181 out of the path of the bolt 192 when the shuttle is at the left-hand side of the loom. This is accomplished in the embodiment of the invention illustrated by providing the detector shaft 177 with the stop lever 199, adapted to engage the stop lever catch 200, which is mounted upon the fixed pivot 201 for rocking movement towards the stop pin 202, see Fig. 3, under the action of the spring 203. The arrangement is such that the stop lever catch when engaged by the stop lever will hold the feeler 174 retracted, as shown in Fig. 3. Means are provided for tripping the stop lever catch 200 as the lay beats up with the shuttle in the filling feeler or right-hand shuttle box. This is accomplished by providing a binder controlled lever 204, which is pivotally mounted upon the stud 205 carried by the lay.

The lever 204 has an upwardly extending finger 206, which rests against the swell or binder 119, as shown in Fig. 3, to be actuated by the movement of the binder. The lever 204 is also provided with the forwardly extending finger 207, the arrangement being such that when a shuttle is in the filling feeler box it will act through the binder to tilt the lever 204 so that the finger 207 will move upwardly sufficiently to strike the lower end 208 of the lever 200 and release the feeler 174 to feel the condition of the filling. When the shuttle is in the left-hand shuttle box as the lay beats up, the swell 119 will not raise the finger 207 to release the feeler 174. The stop lever catch is formed of the two pivoted portions 200 and 208, as shown, which are normally held in vertical alignment with each other by the spring 203, but are so constructed

that the lower end portion may yield rearwardly if engaged by the finger 207 when the lay goes back from the position in which it is shown in dotted lines in Fig. 5 to the position in which it is shown in full lines in this figure. 70

It will be seen from the construction just described that the filling feeler 174 is normally held in its inactive position of Fig. 3 by the stop lever catch 200 and is released by this catch to detect the condition of the filling, only when the shuttle is in the filling detecting box, and the latch is tripped by the finger 207. After the catch 200 has been rocked to release the filling feeler 174, so that the feeler may move to the position in which it is shown in Fig. 5 and effect shuttle replenishment, the feeler will remain in this rearward position until replenishment of filling is effected and the feeler 174 is again pushed forwardly by the filling of a full shuttle, 85 whereupon the stop lever catch 200 will again engage the underface of the stop lever 199, as shown in Fig. 3.

After the empty shuttle has been discharged from the lay and a full shuttle has 90 been substituted therefor, by the transfer mechanism, a trailing end will be left by the full shuttle as it travels from the shuttle magazine through the shed. It is desirable to trim this trailing end adjacent the selvage 95 of the cloth, and means to this end will now be described.

In the embodiment of the invention illustrated filling shearing mechanism is provided adjacent the filling fork, as will be apparent from Fig. 14, and this shearing mechanism comprises a fixed shear plate 209, which is shown as secured to a trough-shaped bracket 210, which is rigidly mounted upon the loom frame to slidably support the filling fork carrier 211. The rocking blade 212 of the shearing mechanism is supported by the pivot pin 213 having the spring 214 which yieldingly holds the movable blade 212 against the fixed plate 209 and serves also to provide sufficient friction between these two blades to maintain the movable blade in the position to which it is moved by its actuating rod 215, which extends downwardly and is connected to an actuating arm upon the rocking shaft 216. The shaft 216 is provided with means, not shown, but adapted to be actuated by the pivoted finger 217 carried by the lay. The arrangement is such that one beat-up movement of the lay causes the finger 217 to rock the shaft 216 in a direction to open the shear blade 212 and the next beat-up of the lay will rock the shaft 216 in the opposite direction to close the movable shear blade and shear the filling end, if the same has been advanced by the moving fabric to a position between the shear blades. 110

It is important that means be provided for stopping the loom upon the occurrence of a mis-pick and to this end in the embodiment 130

of the invention shown a filling fork 218, which may be of the usual construction, is provided and this fork is pivotally mounted at the inner end of the filling fork carrier 211, 5 above described as slidably mounted in the bracket 210. The arrangement is such that when the loom is operating properly and a strand of filling is laid between the downwardly extending prongs of the filling fork 10 and an adjacent portion of the lay, the forwardly extending portion of the filling fork will be rocked upwardly sufficiently to clear a moving actuator, in a well known manner, but when the filling is missing the filling fork 15 will not be tilted and as a result the forward end will be engaged by the actuating member, which will move the slide 211 frontwardly to operate loom control mechanism. In the construction shown the means adapted to engage the filling fork when the filling is missing 20 is a rocking lever 219, the lower end of which is mounted upon a fixed pivot 220, and this lever is yieldingly urged in a rearward direction by means not shown, but is actuated 25 upon every other beat of the lay by the finger 217, to move frontwardly so that a shoulder 221 at the upper end of this lever will engage the filling fork 218 if the filling is missing and pull the fork and slide 211 frontwardly. 30 This forward movement in the construction shown causes a rod 222 at the forward end of the slide 211 to engage a switch actuating lever 223 and shift the same so as to actuate a limit switch enclosed within the 35 casing 224. This switch is supplied with current by conductors within the armored cable 225. The actuation of this limit switch will serve to stop the loom motor in a manner to be described.

40 The loom illustrated in the drawings is provided with wire operating mechanism for the insertion of pile wires in the shed and for removing them from the pile fabric. The pile wire mechanism in the construction 45 shown is mounted at the right-hand side of the loom and is supported by providing this side of the loom with the horizontally extending supporting structure 226 and end frame 227. Upon this supporting structure 50 is mounted the wire slide or carriage runway 228 upon which is slidably mounted the wire operating carriage 229. This carriage is provided with the wire inserting plate 230 and spring actuated wire withdrawing hook 55 231. Upon the upper face of the wire slide 228 is mounted the pivoted, spring operated switch 232, which is adapted to rock about the pivot pin 233. The arrangement is such that when a wire is withdrawn by the hook 60 231 it travels along the guideway 234 and when a wire is inserted by the plate 230 it travels along the inclined path 235.

65 Each time a wire is withdrawn from the pile fabric it is necessary to retract the same far enough to cause its inner end to clear the

butt ends 236 of the row of wires which have not been withdrawn from the fabric, and before the withdrawn wire can again be inserted in the shed its forward end must be shifted rearwardly a substantial distance 70 beyond the row of wires 236.

The present invention contemplates novel means for quickly shifting the forward end of each wire to its rearward position as the inserting operation of the wire is initiated. 75 This is accomplished in the construction shown by supporting a sliding rack 237 above the wire slide 228 for movement transversely of the wire slide and this rack is preferably slidably mounted in the enclosing casing 80 238 supported at the right-hand side of the loom near the front thereof as shown in Fig. 1. The rack 237 is provided at its rear end with a yielding wire engaging finger 239 adapted to engage the forward end of the 85 retract pile wire and move the same rearward into engagement with the wire guide 240, which is supported in a fixed position by the rod 241 adjacent the shed, see Fig. 11. 90 In order to carry the forward end of the rod rearwardly from the position in which it is drawn out of the fabric into the guide 240, it is necessary to thrust the sliding rack 237 rearwardly and this is accomplished by providing the rack with a cooperating gear 242 95 which is secured to and operated by the vertical shaft 243. Rotative movement is imparted to this shaft by providing at its lower end a pinion 244 which meshes with the lower rack 245. When a pile wire is to be inserted the lower rack 245 is thrust frontwardly by cam means, not shown. This movement through the connections just described causes the yielding finger 239 to engage the withdrawn pile wire and carry its forward end 100 rearwardly into the guide 240, and retain the wire in this guide during a part of the time it is being inserted in the shed by the carriage 229. The rear portion of the pile wire may be further guided during its wire inserting position by the auxiliary guide 246 supported as shown above the wire slide 228. The wire inserting mechanism just described 105 operates in a very satisfactory manner to quickly carry the wire rearwardly into position to be inserted in the shed.

The wire retracting carriage 229 should be advanced rapidly in the wire inserting direction but more slowly in the wire retracting direction, so as not to cut the pile forming loops too rapidly during the withdrawal of the pile wire. The operating means shown for imparting this desired movement to the carriage comprises the operating lever 247, the lower end of which is pivotally secured at 110 248 to the bracket 249 extending downwardly from the loom frame 226. The upper end of the lever 247 is operatively connected to the carriage 229 by the yielding connecting link 250. The desired rocking movement is 115 120 125 130

imparted to the lever 247 in the construction shown by the crank arm 251, which is rigidly secured to the operating shaft 252. This shaft is conveniently driven from a bevel gear 253 secured to the bottom shaft 53 and meshes with the bevel pinion 254 provided at the inner end of the shaft 252.

In the weaving of different pile fabrics it may be desirable to adjust the loom so that 10 it will lay either two picks for each row of pile or three picks for each row of pile, and it may also be desirable to weave fabric of different width on the loom. In order to facilitate these changes in the operation of 15 the loom the crank shaft 251 in the construction shown is provided with the adjustable means 255 whereby its effective length may be varied, and the lever supporting bracket 249 is provided with a pivot receiving opening 256, adapted to facilitate the use of a shorter carriage operating lever than that shown in the drawings. The outer end of the crank arm 251 is provided with a head 257 that slidably engages the intermediate portion of the lever 247.

The loom of the present invention is preferably driven by an electric motor 258 which is shown as mounted at the right-hand side of the loom upon the supporting structure 30 for the wire inserting mechanism. The operating shaft of this motor is provided with a pinion 259 that meshes with a gear 260, which may be directly secured to the crank shaft 14. The motor employed to operate 35 the loom should have a high starting torque, and since it is important that the loom shall stop quickly when the power to the motor is cut off, the present motor 258 is shown as having associated therewith an electrically controlled brake, comprising the rotating element 261 secured to the motor shaft and which is positioned to rotate between brake shoes pivotally supported by the rocking levers 262. These levers are continuously 40 urged towards each other in the brake applying direction by the spring 263. The arrangement is such that the brakes are held normally applied and are released by exciting a solenoid within the casing 264 and which 45 operates through the connecting rod 265 to force downwardly the outer end of the lever 266 forming one element of the toggle 267 adapted to force the brake applying levers 262 apart sufficiently to release the brakes 50 from the motor.

Having described the various parts of the loom of the present invention and having pointed out that the loom is driven by an electric motor 258 while the shuttle transfer mechanism is operated by a separate and distinct electric motor 148, one form of wiring for controlling these motors in accordance with the present invention will now be described.

65 Referring to the electric diagram shown in

Fig. 15 of the drawings the circuits disclosed therein are adapted to operate a motor employing a three phase electric current, and the operating current obtained from any suitable source of supply is conducted by the wires 268 to a fuse box 269. The current is supplied from this box to the mechanism to be described by the conductors 1, 2 and 3 upon closing the hand operated switch 270.

The conductors 1, 2 and 3 lead to an electrically operated switch M which controls the current supplied to the loom operating motor 258. The current for releasing the solenoid brake 262 is controlled by the electrically operated switch B, which receives current from two of the three conductors, and is shown as connected to the conductors 1 and 2. The electrically operated switches M and B may be of well known commercial construction and it should be noted that one of the three contact elements of the switch B has no electrical connections, since two conductors are sufficient to control the brake solenoid.

When the switch M is closed current is supplied to the loom motor 258 by the conductors M¹, M², and M³. These conductors lead from the switch M to a terminal board 271 and from the terminal board to the motor 258. Current is supplied from the switch B through the conductors B¹ and B² to the terminal board 271 and from this board to the solenoid brake 262. The construction of the operating switch M is such that it will open automatically but is held closed by exciting the solenoid or control coil CM located adjacent the switch M and included in a control circuit to be described, likewise the operating switch B will open automatically and is controlled by the solenoid or control coil CB included in a circuit to be described. The arrangement is such that the loom operating motor 258 will be started as soon as the coil CM is excited to maintain the switch M closed and this motor will stop when the exciting current to the coil CM is cut off. The brakes for the motor 258, as above stated, are normally applied by spring means. These brakes are released by exciting the control coil CB and are applied to stop the loom and hold it against operation by cutting off the current to the coil CB.

The motor 148 employed to operate the shuttle transfer mechanism may have a much lower horse power than the loom operating motor 258, but is conveniently operated by the current supply conductors 1, 2 and 3, above described, and the current to the motor 148 is controlled by an operating switch S, which may be similar in construction and operation to the switch M, and the operation of the switch S is controlled by a solenoid or control coil CS included in a control circuit to be described. Current is supplied from

the operating switch S to the motor 148 by the conductors S¹, S², and S³, which lead to the terminal board 271 and from this board to the motor 148.

When the loom operating motor 258 is to be started the coil CB is excited to release the brakes and the coil CM is excited to close the switch M that supplies current to the motor 258. It is important that means be provided for manually starting and stopping the loom, and it is also desirable that means be provided for stopping the loom when a defect in the weaving operation occurs, for example, the loom should be stopped when either of the warp stop mechanisms 33 or 34, above described, detect a broken or excessively slack warp strand. The loom should also be stopped when the filling fork 218 detects the absence of filling and operates the loom switch within the casing 224.

It is important that the loom be stopped if a shuttle is improperly boxed and this may be accomplished by providing the usual dagger controlled by the shuttle box binder and adapted to engage a frog in a well-known manner to stop the loom when a shuttle is not properly boxed, but it is also desirable to provide the present electrically operated loom with switch mechanism to stop the driving motor when a shuttle is improperly boxed.

The electrical connections whereby the loom will stop and the brakes will be applied when any of the defects above mentioned occur, will now be described.

In order to secure the desired manual control of the loom operating motor the loom illustrated in the drawings is provided with the switch box 272, conveniently located at the front of the loom adjacent the wire operating mechanism and upon this switch box is pivotally mounted a hand operated lever 273 which when rocked in one direction will depress a push button 274 to start the loom, and when rocked in the opposite direction will depress a push button 275 to stop the loom.

In addition to the manually controlled switch mechanism just mentioned means are provided, as above described, whereby when the filling feeler 174 detects substantial exhaustion of filling the switch mechanism in the switch box 197 will be operated to first stop the loom motor 258 and then start the shuttle transfer motor 148, and after the shuttle transfer operation has been completed, it is important that means be provided for automatically stopping the motor 148 and starting the loom motor. The switch mechanism last mentioned is shown as enclosed in a switch box 276 conveniently mounted upon the gear box case 150 and protected by the housing 277. The switch 276 is operated by a cam 278 secured to the cam shaft 158 and this cam is so constructed that as the shaft 158 completes its cycle of rotation a project-

ing nose upon the cam 278 will force the spring depressed plunger 279 upwardly to rock the switch arm 280 and actuate the switch mechanism within the box 276 to thereby stop the motor 148 and start the motor 258 in a manner to be described.

It is important that means be provided for preventing the loom from being started during the operation of the shuttle transfer mechanism. This is accomplished in accordance with the present invention by providing the shaft 158 with a fourth cam 281, the outer periphery of which has the contour of a circle except for a depression 282 provided therein. The arrangement is such that the loom motor 258 may be operated only when the spring depressed plunger 283 rests in the depression 282, and as a result this plunger is held elevated until the cam 281 is rotated through a complete cycle and the plunger again drops in the depression 282. As long as the plunger 283 is elevated, a switch within the switch box 284 will be held open so that the loom motor cannot be started.

In some cases in operating the loom of the present invention it may be desirable to release the solenoid control brake without starting the loom motor, so that the motor may be turned over by hand. In order to accomplish this a master switch is provided and is shown in Fig. 1 as mounted at the front of the loom within the casing 285. Within this casing is provided the switch operating shaft 286 which is provided at its outer end with a handle 287, and the arrangement is such that if this handle is rocked to the position "I", both the loom operating motor and brake will be under the control of a hand operating lever 273, whereas if the handle 287 is rocked to the position "II" the electric brake alone will be under the control of the hand operated lever 273. When the handle 287 is rocked to the "O" position all circuits are open.

To the rocking shaft 286 are secured the three closure plates 288, 289 and 290 arranged so that when the shaft 286 is rocked to one position, to be described, these plates will engage one set of contacts, and when the shaft is rocked in the opposite direction they will engage the other set of contacts.

The electrical connections for placing the three electrically operated switches M, B and S under the control of the master switch 287, hand operated lever 273, shuttle transfer switch 197, transfer motor stopping switch 276 and various limit switches will now be described.

Let it be assumed that the loom is to be started; this is accomplished by shifting the master switch from its "O" or central position of Fig. 15 to the "I" position of Fig. 16, and by shifting the hand lever 273 to the right (Fig. 1) to depress the starting switch 274 from its normally raised position to its

lowered or dotted line position of (Fig. 15). Current will then flow from the closed switch 270 through conductors *d*, lowered starting switch 274, conductor *e*, stopping switch 275, which is normally held closed, as shown, conductor *f*, upper switch of switch box 197 (which is normally held closed as shown) and through conductor *g* to switch 284 which is normally closed but is held open during the operation of motor 148.

The current passes from switch 284 through *h* to the limit switch WS of the warp stop mechanism 33; limit switch W' S' of the warp stop mechanism 34; limit switch FF of the filling fork control mechanism 224; and a limit switch BF of the binder finger control switch above mentioned. These limit switches are connected, in series, and are all closed when the loom is in proper operating condition, and permits the current to pass through the conductors *h* to the contact points *a*², and *a*³ of the master switch. From these points the current flows through the closures 289 and 290 and conductors *i* and *j* to the control coils CM and CB connected to the conductor 2. This completes the circuit between conductors 1 and 2 and excites the coils CM and CB to close the electrically operated switches M and B to release the brakes and start the loom motor.

The circuit just described will remain closed only momentarily, since as soon as the hand lever 273 is released by the machine attendant it will automatically move to its central position of Fig. 1 and the start switch 274 will return to its full line position of Fig. 15.

To take care of this, the electrically operated switch M is provided with an auxiliary contact switch *k* that is opened and closed with the switch M, and the switch B is provided with a similar auxiliary contact switch *k'*. The contact switches *k*, *k'* are connected by the wide *l'*, to which wire is connected the conductor *m*. Connected in series by the conductor *m* are the thermal relays R¹, R² of well known construction, and they are arranged between coils in the circuits, M¹, M³ and B¹, B² respectively, as shown. The arrangement is such that these relays will open the circuit and stop the loom in case of an overload.

When the start button 274 returns to its full line position of Fig. 15 after closing the switches M and B by exciting the coils CM and CB, the current for exciting these coils will flow from conductor 1 through switch *k* or *k'* and through *m* to the closed stopping switch 275. From this switch the current will flow through the series of limit switches and other circuits, as above described, to the coils CM and CB through *j* and *i* respectively.

The loom may be stopped by rocking the

hand lever 273 to the left to open the stop switch 275, or by the opening of any one of the limit switches in the circuit *h*, or by the opening of a relay switch R¹, R² or the master switch 287.

When it is desired to release the brakes 262 without starting the loom motor 258, so that the loom may be turned over by hand the master switch is rocked to the "II" position so that the circuit controlling the coil CB will remain under the control of the starting button 274 and stopping button 275 but the circuit for controlling the coil CM will remain open. The shifting of the master switch to this last mentioned position will serve also to shunt the limit switches WS, W' S', FF and BF, so that the brakes may be released even if one or more of these switches are held open by a defective condition of the loom.

If the hand operated lever 273 is operated to depress the starting switch 274 current will flow through the circuits above described from the conductor 1 to the switch 284 and from this switch through *h* and shunt wire *n* to contact *a*⁴ and then through closure 288 and conductors *P*, *h* to contact *a*⁵. If then flows from *a*⁵ through closure 289 and conductor *i* to coil CB but not to coil CM.

Having described the controlling mechanism for the loom motor 258 and brakes 262, the mechanism for automatically controlling the motor 148 so as to start the same and stop the loom motor when shuttle replenishment is called, and to stop the motor 148 and start the loom when the shuttle replenishing operation is completed, will now be described.

The electrically operated switch S for the motor 148 is controlled by the coil CS connected to the conductor 1 by the wire *g*, and this wire is provided with the thermal relay R³ for stopping the motor 148 in case of overload. The conductor *q* leads to the lower normally closed switch of the switch box 276 and this switch is connected to the normally closed starting switch 274 by the conductor *r*. The switch 274 is connected by the conductor *s* to the lower and normally open switch of the switch box 197, and this last mentioned switch is connected by the conductor *t* to the conductor 3. The upper switch of the switch box 276 is normally open as shown, and controls the circuit *u* between the conductor *m* and starting switch 274. The upper and lower switches of the switch box 197 are mechanically connected as shown so that they move together and the circuit controlled by one switch is opened before the circuit controlled by the other switch is closed. The same is true also of the switches in the switch box 276.

When the filling feeler 174 detects substantial exhaustion of filling it will position the pivoted latch 181, as above described, to be struck by the lay. This will rotate the

toothed cam wheel 195 to momentarily open the upper switch and close the lower switch of switch box 197. Current may then flow from 3 to t , lower switch of 197, s , starting switch 274, r , lower switch of 276 and through q and coil CS to conductor 1. This excites coil CS long enough to close the electrically operated switch S, which may be similar to switch M, and start the motor 148, whereupon the auxiliary switch v is closed. Current may then flow by way of 3 through v , w , s , 274, r , lower switch of 276, q and the coil CS to 1.

When the cam carrying shaft 158 has been rotated by the motor 148 through a complete cycle, the switches of switch box 276 will be momentarily shifted by the cam 278. This will open the lower switch of switch box 276 to cut off the current to the coil CS and stop the motor 148. It will also close the upper switch of the switch box 276, whereupon current may flow from *d* to *e* through *u*, and from 275 to *f* and *g* and the master switch to release the brakes and start the loom motor as above described.

25 as above described.
The loom is readily controlled through the
electrical connections above described, and is
quickly stopped when any one of the limit
switches is actuated as a result of a defect
30 in the loom operation, or when shuttle re-
plenishment is called for by the filling feel-
ing mechanism.

What is claimed is:

Claims:

35 1. In a carpet loom having an automatic shuttle replenishing mechanism, in combination, a lay provided with shuttle boxes, a shuttle magazine, means for ejecting an exhausted shuttle from a shuttle box and for inserting a full shuttle therein, filling feeling mechanism for initiating shuttle transfer, a driving motor for the loom, a separate motor for operating the shuttle transfer mechanism, and means controlled by the filling feeling mechanism for starting the motor that operates the shuttle transfer mechanism.

2. In an automatic shuttle replenishing loom, in combination, a lay provided with shuttle boxes, a shuttle magazine, means for discharging an exhausted shuttle from a shuttle box and for inserting a full shuttle therein, filling feeling mechanism for initiating shuttle transfer, power means for operating the loom, an electric motor for operating the shuttle transfer mechanism and means for starting the motor to effect shuttle transfer and for stopping the motor as soon as the transfer is completed.

60 transfer is completed.

65 3. In an automatic shuttle replenishing loom, in combination, a lay provided with shuttle boxes, a shuttle magazine, means for discharging an exhausted shuttle from a shuttle box and for inserting a full shuttle therein, filling feeling mechanism for initiating shuttle transfer, a driving motor for the

loom, a separate motor for operating the shuttle transfer mechanism, and means controlled by the filling feeling mechanism for stopping the loom and starting the motor that operates the shuttle transfer mechanism. 70

4. In an automatic shuttle replenishing loom, in combination, a lay provided with shuttle boxes, a shuttle magazine, means for discharging an exhausted shuttle from a shuttle box and for inserting a full shuttle therein, a driving motor for the loom, a separate motor for operating the shuttle transfer mechanism, and filling feeling mechanism for initiating shuttle transfer and provided with switch means for stopping the loom motor and starting the shuttle transfer motor when substantial exhaustion of filling is detected. 75 80

5. In an automatic shuttle replenishing loom, in combination, a lay provided with shuttle boxes, a shuttle magazine, means for discharging an exhausted shuttle from a shuttle box and for inserting a full shuttle therein, a driving motor for the loom, a separate motor for operating the shuttle transfer mechanism, filling feeling mechanism operable to stop the loom motor and start the shuttle transfer motor when substantial exhaustion of filling is detected, and means operable by the shuttle transfer motor as the transfer is completed to stop this motor and start the loom operating motor.

6. In an automatic shuttle replenishing loom, in combination, a lay provided with shuttle boxes, a shuttle magazine, means for discharging an exhausted shuttle from a shuttle box and for inserting a full shuttle therein, a driving motor for the loom, a separate motor for operating the shuttle transfer mechanism, filling feeling mechanism operable to stop the loom motor and start the shuttle transfer motor when substantial exhaustion of filling is detected, and means under the control of the shuttle transfer motor for preventing the loom motor from being started during the shuttle transfer operations. 100 105 110

7. In an automatic shuttle replenishing loom, in combination, a lay provided with shuttle boxes, a shuttle magazine, means for discharging an exhausted shuttle from a shuttle box and for inserting a full shuttle therein, filling feeling mechanism, a driving motor for the loom, an electrically controlled brake associated with the motor to stop the loom quickly, a separate motor for operating the shuttle transfer mechanism, switches for controlling the brake and motors, switch actuating mechanism operable to stop the loom motor, apply the brake and start the shuttle transfer motor, and means controlled by the filling feeler to initiate the shuttle transfer operations.

8. In an automatic shuttle replenishing loom, in combination, a lay provided with shuttle boxes, a shuttle magazine, means for

- discharging an exhausted shuttle from a shuttle box and for inserting a full shuttle therein, filling feeling mechanism, a driving motor for the loom, an electrically controlled brake associated with the motor to stop the loom quickly, a separate motor for operating the shuttle transfer mechanism, switches for controlling the brake and motors, switch actuating mechanism operable to stop the loom motor, apply the brake and start the shuttle transfer motor, and means controlled by the filling feeler to initiate the shuttle transfer operations.
9. In an automatic shuttle replenishing loom, in combination, a lay provided with shuttle boxes, a shuttle magazine, means for discharging an exhausted shuttle from a shuttle box and for inserting a full shuttle therein, filling feeling mechanism, a driving motor for the loom, an electrically controlled brake associated with the motor to stop the loom quickly, a separate motor for operating the shuttle transfer mechanism, means controlled by the filling feeling mechanism to stop the loom motor, apply the brake and start the shuttle transfer motor, and means operable by the last mentioned motor to stop the same upon completion of the shuttle transfer and start the loom.
10. In an automatic shuttle replenishing loom, in combination, a lay provided with shuttle boxes, a shuttle magazine, means for discharging an exhausted shuttle from a shuttle box and for inserting a full shuttle therein, power means for operating the loom, a separate motor for operating the shuttle transfer mechanism, an electric switch for starting said motor, means upon the lay for actuating the switch to effect shuttle transfer, and filling feeling mechanism constructed and arranged to cause the lay to actuate the switch only when substantial exhaustion of filling is detected.
11. In an automatic shuttle replenishing loom, in combination, a lay provided with shuttle boxes, a shuttle magazine, means for discharging an exhausted shuttle from a shuttle box and for inserting a full shuttle therein, power means for operating the loom, a separate motor for operating the shuttle transfer mechanism, an electrically operable switch for controlling said motor, an electric circuit for actuating said switch, a controlling switch for said circuit, and filling feeling mechanism adapted to actuate said last mentioned switch to start the motor when substantial exhaustion of filling is detected.
12. In an automatic shuttle replenishing loom, in combination, a lay provided with shuttle boxes, a shuttle magazine, means for discharging an exhausted shuttle from a shuttle box and for inserting a full shuttle therein, filling controlled mechanism for initiating shuttle transfer, power means for operating the loom, an electric motor for operating the shuttle transfer mechanism, and means including said filling controlled mechanism for starting said motor to effect shuttle transfer.
13. In an automatic shuttle replenishing loom, in combination, a lay provided with shuttle boxes, a shuttle supply hopper, means for discharging an exhausted shuttle from a shuttle box and for inserting a full shuttle therein, filling controlled mechanism for initiating shuttle transfer, power means for operating the loom, an electric motor for operating the shuttle transfer mechanism, and means including said filling controlled mechanism and operable upon the occurrence of substantial filling exhaustion to quickly stop the loom and start said motor.
14. In an automatic shuttle replenishing loom, in combination, a lay provided with shuttle boxes, shuttle replenishing mechanism operable to eject an empty shuttle from a shuttle box and insert a full shuttle, power operating mechanism for the loom, a separate and independent motor for operating the shuttle replenishing mechanism, and filling feeling mechanism for starting said motor to effect shuttle replenishment.
15. In an automatic shuttle replenishing loom, in combination, a lay provided with shuttle boxes, a shuttle magazine, shuttle supporting means mounted beneath the hopper for movement into and out of shuttle supporting position, a transerrer for transferring a full shuttle from the magazine to a shuttle box and adapted to move said shuttle supporting means to the shuttle releasing position, and an auxiliary shuttle support movably mounted below said transerrer and shuttle supporting means and adapted to catch any shuttle that is accidentally released from the magazine, and support the same so that it will not be delivered to the transerrer.
16. In an automatic shuttle replenishing loom, in combination, a lay provided with shuttle boxes, shuttle replenishing mechanism operable to eject an empty shuttle from a shuttle box and insert a full shuttle, a driving motor for the loom, a separate and independent motor for operating the shuttle replenishing mechanism, means for stopping the loom operating motor and starting the replenishing motor to effect shuttle transfer, and separate means for preventing current from being supplied to both motors at the same time.
17. In an automatic shuttle replenishing loom, in combination, a lay provided with shuttle boxes, shuttle replenishing mechanism operable to eject an empty shuttle from a shuttle box and insert a full shuttle, a driving motor for the loom, a separate and independent motor for operating the shuttle replenishing mechanism, a controlling switch

for each motor, and a pair of cooperating switches connected in the circuits for the two motors and arranged to open one motor circuit before closing the other motor circuit.

In testimony whereof, I have signed my
5 name to this specification.

EDWIN W. STONE.
